UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,248,534.

Specification of Letters Patent.

Patented Dec. 4, 1917.

Application filed April 9, 1917. Serial No. 160,647.

To all whom it may concern:

Be it known that I, JOHN F. O'CONNOR, a citizen of the United States, residing at Chicago, in the county of Cook and State of Illinois, have invented a certain new and useful Improvement in Draft-Riggings for Railway-Cars, of which the following is a full, clear, concise, and exact description, reference being had to the accompanying drawings, forming a part of this specification.

This invention relates to improvements in draft gears for railways cars.

One object of the invention is to provide a friction draft gear for railway cars wherein are employed frusto-conical friction springs coöperable with correspondingly formed friction shells and an ordinary coil spring to thereby produce a large amount of friction upon relative approach of the followers between which the gear proper is mounted.

Another object of the invention is to provide a friction gear employing a frusto-conical friction spring in combination with other elements so arranged as to produce friction between the layers of the spring itself, between the spring and an exterior member and an additional lineal resistance of said spring as an entirety.

In the drawing forming a part of this specification, Figure 1 is a horizontal longitudinal section of a portion of a draft rigging showing my improvements in connection therewith, the parts being indicated in normal or full release position. Fig. 2 is a view corresponding to Fig. 1 but illustrating the position of the parts under full buff. And Fig. 3 is a vertical transverse section, 40 taken on the line 3-3 of Fig. 1.

In said drawing, 10-10 denote channel-shaped center sills to the inner faces of which are secured rear stops 11 and front stops 12. Coöperable with said stops is a 45 rear follower 13 and front follower 14, the followers and the gear therebetween being connected to the draw bar 15 by a yoke 16.

The gear proper, as shown, comprises a longitudinally slidable casting A, more particularly hereinafter described, frusto-conical springs B-B at each end thereof, inner spring followers C-C, a longitudinal coil spring D, friction blocks E-E and a retaining bolt F.

55 The casting A is provided at each end

thereof with a conical mouth 17 which tapers inwardly toward the center of the casting and said casting is of such a length as to permit the full desired movement of the gear. At the inner ends of each of the conical-shaped mouths 17, the casting A is provided with interior shoulders 18-18 against which the followers C-C normally bear, and it will be understood that the followers C-C are supported and guided in their movements back and forth by the upper and lower walls 19-19 of the casting A. Each frusto-conical spring B consists of a plurality of spring plates 20-20, the latter being each bent to conform to the surface of a frusto-cone with clearance as indicated at 21-21 between the edges of each plate to thereby permit the latter to collapse in the operation of the gear, as will be understood.

The plates are preferably arranged as indicated most clearly in Fig. 3, that is, with the edges of one plate on one side and the edges of the next adjacent plate diametrically opposite, so that all the plates overlap each other and insure proper contraction or collapse of all the plates as the latter are pressed inwardly. The inner ends of the frusto-conical springs B-B normally bear against the followers C-C and in order to insure the springs B-B being maintained in proper position or fully expanded, the friction blocks E-E are seated therewithin, as clearly indicated in Figs. 1 and 2. The coil spring D is interposed between the follower C-C, as shown in Fig. 1.

With the parts in the position shown in Fig. 1 wherein the outer ends of the springs B-B are normally extended beyond the corresponding adjacent ends of the casting A, relative approaching movement between the followers 13 and 14 will force the frusto-conical springs B-B inwardly. During this action, it is apparent that friction is created between the springs B-B and the casting A on their exterior and between the springs B-B and the friction blocks E-E on their interior.

In addition to the foregoing generated friction, additional friction is produced between the plates composing the springs B-B as the latter contract while being forced into the conical mouths 17-17. To still further augment the resistance and increase the capacity of the gear, the springs B-B force the followers C-C inwardly.

against the resistance of the coil spring D. Upon removal of the buffing or draft pressure on the followers, the coil spring D will separate the followers C—C and consequently force the springs B—B outwardly and the latter will act as spring dampeners during this release action, due to the friction generated between the relatively sliding coils of each frusto-conical spring B. The entire gear may be supported in any suitable manner, as by the saddle plate 22, which is detachably connected to the lower flanges of the sills.

I claim:

- 15 1. In a device of the character described, the combination with a friction shell having a conical friction surface, of a frusto-conical compressible friction member coöperable therewith, and springs interposed between said shell and said member for resisting relative movement therebetween.
- 20 2. In a device of the character described, the combination with a friction shell having an interior conical friction surface, of a frusto-conical hollow compressible friction member coöperable therewith on its exterior, a friction block disposed on the interior of said member and coöperable therewith, and a spring interposed between said shell and said member for resisting relative movement therebetween.
- 25 3. In shock absorbing mechanism, the combination with a casting having a conical friction surface at each end thereof, of a frusto-conical compressible friction member
- 30
- 35

coöperable with each of said surfaces, and a spring interposed between the inner ends of said members to thereby resist relative movement between said members and said casting.

4. In shock absorbing mechanism, the combination with a casting having a conical shaped mouth at each end thereof with a chamber located intermediately of said mouths, of a spring mounted within said chamber, a frusto-conical compressible friction member disposed within and coöperable with each of said mouths on its exterior, and a friction block disposed on the interior of each of said members and coöperable therewith.

5. In shock absorbing mechanism, the combination with a casting having a conical shaped mouth at each end thereof forming a friction shell, said casting having a chamber intermediate said mouths, of a spring located within said chamber, followers at the ends of said spring, frusto-conical springs disposed in each of said mouths, said frusto-conical springs having their outer ends extended normally beyond the ends of the casting and their inner ends bearing against the corresponding adjacent spring follower, and a friction block disposed within each of said frusto-conical springs.

In witness that I claim the foregoing I have hereunto subscribed my name this twentieth day of March, 1917.

JOHN F. O'CONNOR.
